CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK

TRAIN CONTROL

Application filed March 9, 1922. Serial No. 542,270.

This invention relates to automatic train control systems for railroads, and more particularly to that part of such systems which involves the transmission or communication of control impulses or influences from the trackway to moving vehicles.

One of the essential elements of any type of automatic train control system is an efficient and reliable means for communicating or transferring suitable control impulses or influences from the trackway to a moving locomotive or other vehicle under the unfavorable conditions of high speed, exposure to weather, close clearances, and the like, found in practice. On account of the difficult conditions to be satisfied, it is considered desirable to communicate such control influences through an intervening space or air gap between parts on the track and parts on the vehicle, rather than by direct mechanical cooperation or physical contact. The principle of magnetic or electro-magnetic induction is, it is believed, especially adapted for this purpose.

In connection with such an inductive system, it is thought to be preferable, for various reasons, to use a track device which does not require the supply of electrical energy from the trackway while in either the active or inactive condition. Such a track device, in the interests of safety, must also be of such a character that so far as practicable, any failure of circuits or contacts, breakdown of insulation and other defects at all likely to occur in practice, should be on the side of safety, that is, cause the track device to produce a stopping control. Further, in order to avoid false operation and delays, the nature of the track device should be such that its influence on the apparatus on the vehicle is different and distinctive from the influence of anything else ordinarily encountered along the trackway, more particularly the track rails of switches and crossings, and similar magnetic bodies.

To meet these various requisites, it is proposed in accordance with the present invention, to produce the desired control influence by the action of a magnetic field existing on the track under dangerous traffic conditions

upon a suitable receiving device on the vehicle; and in order to obviate the need for electrical energy to create or determine the existence of this field of flux, it is contemplated that such field will be produced by a current temporarily induced in a trackway circuit by the action of a field of flux carried by the vehicle upon a cooperating track element. According to one specific embodiment of the invention, this general scheme or principle of operation is carried out by a car-carried field or primary element constituting a source of flux which cooperates with a generating or inducting track element to produce in the latter a current, by providing another transmitting or sending track element, to which this current is conducted under dangerous traffic conditions, and which acts to create a magnetic field adapted to cooperate with a flux responsive receiving element on the car, the response of the receiving element and associated devices being utilized to exert the desired control of the vehicle. In this particular embodiment of the invention, the trackway equipment, comprising the generating or inducting element and the sending or transmitting element, is put in the inactive or non-stopping condition, corresponding to clear traffic conditions, by breaking or stopping the transmission of current between the generating element and the sending element, preferably by placing a shunt of low resistance across the coils or windings of this sending element.

In the type of influence communicating means just outlined, it will be evident that the field or primary element on the vehicle will tend to magnetize switch points, track rails of crossings, and similar iron bodies along the track in passing over them; and under unfavorable conditions, the residual flux of such iron bodies, if properly disposed or located, will produce upon the receiving element on the vehicle an effect of the same nature as that of the sending element on the track. In other words, the residual magnetism in track rails and the like, will tend to cause premature or false operation of the car equipment. To obviate the possibility of such interference with the desired operation by

magnetized rails or the like, it is contemplated that the two pairs of cooperating elements on the track and on the vehicle will be disposed in a different relation with respect to the track rails, so that any residual magnetism on the track created by the field element on the vehicle will be unable to affect the receiving element on the vehicle, while at the same time the track sending element will be in such position to cooperate effectively with said vehicle carried receiving element.

In the typical embodiment of the invention above described, it will be observed that the transmission of the desired controlling influences is dependent upon integrity of the coils or windings of the generating and sending elements on the track, and the electrical connections between these elements over which the induced current is conducted; and while the parts of these circuits can be carefully constructed with ample margin in strength and insulating qualities, so that a breakdown is no more likely to occur than in any other mechanical structure, it is proposed to provide a scheme of automatically checking up the performance of these circuits, and in case defect is detected, to automatically govern train movements on the side of safety. Generally speaking, this scheme of checking or detecting failure consists in sending current through the coils and wires on which the safety of the system depends, and in case of defect, to obviate the possibility of accident on account of such defect by arresting or slowing down each train at the next control point in the rear, thereby assuring that such train will not run into any train that may be directly ahead of the defective track devices and depend on them for protection. Another characteristic of this automatic checking scheme is that as soon as a failure or defect exists, each train will be slowed down or stopped at a point in the rear until things are fixed.

The various particular objects and characteristic features of the invention will be in part apparent from the foregoing discussion, and will appear as the detailed description progresses.

In describing the invention in detail, reference will be made to the accompanying drawings, in which:-

Fig. 1 shows diagrammatically and in a simplified manner one form of the track devices and circuits constituting one embodiment of the invention;

Fig. 2 shows diagrammatically one form of the car equipment and the manner of co-operation of the car-carried and trackway equipment;

Fig. 3 is a diagrammatic illustration similar to Fig. 2 showing a modified construction;

Fig. 4 illustrates a modified form of a

car-carried apparatus in which the thermionic amplifier has been omitted;

Fig. 5 illustrates another modified form of car-carried apparatus in which the receiving element directly actuates contacts carried thereby;

Fig. 6 illustrates a modified form of car-carried apparatus of the type shown in Fig. 5;

Fig. 7 illustrates a modified form of field element in connection with the car-carried system illustrated in Fig. 4;

Fig. 7-A is a curve of induced voltage obtained by the car apparatus of Fig. 7; and

Fig. 8 to 17 illustrate diagrammatically various ways in which the generating track element and the sending track element may be located with respect to each other and with respect to the trackway.

Various arrangements of trackway circuits for controlling the condition of the trackway devices may be employed, and in the accompanying drawings there is shown only one typical arrangement. Referring to Fig. 1, the track rails 1 are divided by insulated joints 2 into blocks in the usual way, one block I and the adjacent ends of two other blocks H and J being shown. Since the parts associated with the various blocks are the same, for convenience they will be given like reference characters with distinctive exponents. Each of the blocks is provided with a track battery 3 and a track relay 4 in the same way as in the ordinary block signal systems.

Since it is contemplated that a train control system should preferably be an adjunct to a block signaling system, rather than as a substitute for such a system, the usual fixed trackway signals are shown in connection with the train control system of this invention. As a typical illustration, one particular form of a semaphore signal has been illustrated conventionally, namely, a three-position with neutral line relay control. It should, however, be understood that any other form of three-position signals, or two-position signals, may be employed equally as well. This signal S has been shown diagrammatically because its specific construction is no part of the present invention, and may be any one of the well-known forms in common use. In the typical semaphore signal, the semaphore arm of the signal S is biased by its own weight to the horizontal or stop position, conveniently called the zero degree position;

The specific mechanism for operating the signal has not been illustrated because it is no part of the present invention; but in general this mechanism comprises a motor, gearing, hold clear device, and automatic circuit controllers, all organized so as to cause the semaphore blade to be driven in opposition to its bias to an inclined, caution, or 45 degree position and held there, or still further driven to a vertical, clear or 90 degree position, these

movements being obtained by supplying current to a caution or 45 degree control circuit to actuate it to said first or caution position, and by supplying current to a 90 degree control circuit to actuate it to its 90 degree or clear position shown in Fig. 1 of the drawings. These control circuits are shown diagrammatically as leading to the semaphore blade itself, and the position at any time 5 through the various steps of the operation of the device may be determined by observing whether current is being supplied to the 45 degree control circuit, which would bring the semaphore to the 45 degree position, or if 10 current is supplied to both the 45 degree circuit and the 90 degree circuit, which would bring the semaphore to its clear or 90 degree position, or if both of these circuits are de-energized, which would cause the semaphore 15 to assume the zero degree or danger position.

In Fig. 1 of the drawings are shown diagrammatically three independent circuit controllers, which in practice would usually comprise a single controller drum having three independent controller segments and stationary contact fingers therefor. One of these 25 circuit controllers will for convenience be called the checking circuit controller, and comprises a stationary segment 5 which will be in contact with a movable circuit controller arm 6 between zero and α degrees, where α represents an angle of something less than 45 degrees. Another circuit controller, which 30 will be termed the clearing circuit controller, comprises a segment 7 which will be contacted by a circuit controller arm 8 between α and 90 degrees. A third circuit controller, which will be termed the line circuit controller, comprises a segment 9 which will be contacted by 35 a contact arm 10 substantially between the 45 degree and 90 degree position. In the diagrammatic illustration of the circuit controllers, the movable arm will in each instance 40 be parallel to the semaphore blade, and as illustrated in Fig. 1, the semaphore blade and each of these arms is in its 90 degree or clear 45 position.

Each of the blocks is provided with a line 50 relay 11, and while polarized line circuits or any other well-known expedient for controlling the cautionary or distant indication may be employed, in the particular construction illustrated a neutral line relay is used, the 55 energizing circuit for the line relay of block I being as follows:—Starting from the terminal P of a battery, segment 9¹ and contact arm 10¹ of the line circuit controller of signal S¹, wire 12¹, front contact 13¹ of track relay 4¹, 60 line wire 14¹, front contact 15 of track relay 4 of block I, wire 16, winding of the line relay 11, to the common return wire.

At the entrance of each block is located a 65 pair of track elements, one of which is shown mounted crosswise of the track adjacent the

entrance of each block. This track element is adapted to be influenced by a cooperating car element, and will for convenience be referred to as a generating or induction element L. A short distance in the rear of this generating or induction element L is another similar element located lengthwise of the trackway, which will be referred to as a sending or transmitting element T. These track elements L and T each comprise a U-shaped soft iron core, preferably laminated to reduce the harmful effects of eddy currents, the upstanding legs being provided with enlarged pole pieces, and each having thereon a coil or winding 17. The coils 17 of each track element L and T are wound and connected in a manner so that the voltages induced in these coils due to a change of flux in the core thereof will be cumulative.

The coils 17 of the induction element L and the transmitting element T are connected in a closed or loop circuit. Since the transmission of a controlling influence by these track elements is dependent upon the integrity of this loop circuit, it is contemplated that this circuit will be made up in practice of wires of large size, preferably stranded, well insulated and armoured, for the purpose of reducing the possibility of failure of this circuit. To further safeguard this loop circuit against weather, insects and tampering, the wires are preferably housed in a conduit and made as short as practicable.

Although this loop circuit can, it is believed, be made as dependable as any mechanical mechanism by care in design and construction, it is proposed to provide, as an additional safeguard against failure of the train control system by accidental breakage or injury to the wires of this circuit, a scheme or system for automatically checking up the integrity of this loop circuit at each train movement, and in case of failure cause automatic control of following trains on the side of safety. For this purpose checking relays 18 and 19 are employed. These check relays are illustrated conventionally; but they should be designed with operating characteristics to especially adapt them for their purpose by making their impedance as low as possible, and preferably by providing balanced moving elements to prevent their actuation due to vibration of passing trains to which they will be subjected. Two check relays 18 and 19 are preferably used, because 100 the checking current through this loop circuit can then be passed through the two halves of the circuit in multiple and without providing switches in this circuit, that is, 105 by passing a current from one side of the closed loop to the other side of the same in a manner so that each branch of the circuit 110 passes through a check relay.

For the purpose of understanding the operation and utility of the devices illustrated 115

130

in Fig. 1, the operation thereof will be presently explained; but in order to understand the purpose of the track elements, the car-carried devices which coact therewith will be briefly referred to. Generally stated, the car-carried apparatus comprises a pair of car elements very similar to the generating and sending track elements. One of these car elements, which will be known as the field or primary element F, is located on the vehicle crosswise of the track in cooperative relation to the generating or induction element L. This field element F is normally energized by a direct current producing a constant field of flux emanating in the direction of the track element. The other car-carried detecting or receiving element D is mounted lengthwise of the vehicle so as to be in cooperative relationship with the sending or transmitting element T at the time when the field element F is in cooperative relation with the induction element L. This detecting element D is provided with flux responsive means adapted to control the train in any suitable manner. Thus, when the field or primary element F passes over the generator or induction element L, a momentary current will flow in the loop circuit, thus producing a variable magnetic field in the transmitting element T, which in turn produces a momentary change of flux in the flux responsive means of the receiving or detecting element D.

Operation of Fig. 1.—Assuming that no trains are present in blocks I or J, the position of the various devices and the condition of the various circuits in Fig. 1 will be normal, as illustrated in the drawings. The operation of the parts and circuits associated with each block are the same, so that a description of this operation in connection with the block I will apply to the other blocks and will show how train movements are governed automatically on all parts of the railroad equipped.

The coils 17 of the track elements L and T are connected together in the loop circuit hereinbefore mentioned, this circuit as shown in Fig. 1 being traced as follows:—Commencing at the upper coil 17 of the track element L, wires 20 and 21, checking relay 18, wire 22, coil 17 of track element T, wires 23 and 24, other coil of said element T, wire 25, other checking relay 19, wires 26 and 27, other coil 17 of element L, and wires 28 and 29.

In the specific type of block signal system illustrated, the several signals S are maintained in the vertical or clear position normally, that is, when no trains are present. The control circuits for these signals are the same, and a description of those associated with signal S at the entrance to block I will suffice for all. For the purpose of simplicity, these control circuits for the signals,

and also the circuits associated with and governing the track elements, have been shown in a conventional manner, the reference characters P and N indicating direct connections to opposite terminals of a battery or other source of current, it being understood that these respective circuits are connected to different batteries of the proper voltage, or wholly or in part to the same battery in conformity with recognized practice.

The circuit which supplies current to the operating mechanism of signal S and serves to maintain that signal in its normal clear position, conveniently termed the 90 degree control circuit, may be traced on the drawings as follows:—Commencing at P, circuit controller 7—8, wires 30 and 31, front contact 32 of track relay 4, wires 33 and 34, front contact 35 of line relay 11, wire 36 to the signal mechanism (not shown), and thence to N.

The circuit for holding the semaphore signal S in the inclined or caution position, conveniently called the 45 degree control circuit, may be traced in the drawings as follows:—Commencing at P, circuit controller 7—8, wires 30 and 31, front contact 32, and wires 33 and 37 to the signal mechanism and thence to N.

Under clear traffic conditions, that is, when no train is present in either of the blocks I or J, the coils 17 of the track element L at entrance to block I are shunted by a clear or proceed governing circuit of low resistance, comprising wires 38 and 39 and front contact 40 of line relay 11, so that with said line relay picked up, the coils 17 of the track element L are included in a closed circuit of low resistance, the complete circuit being traced as follows:—Commencing at the upper coil 17, wires 20 and 38, front contact 40, wires 39 and 27, other coil 17, wires 28 and 29.

Assume that a train is in the block H moving in the direction of the arrow. As this train advances into the block I, the track relay 4 will be robbed of its energizing current, causing its four front contacts to open. The opening of front contact 15 causes the line relay 11 to be deenergized, thereby opening its front contact 40 and in turn opening the low resistance shunting circuit around the coils 17 of the generating element L. This places the track elements L and T in their active stopping condition to transmit a stopping influence to a passing train in the manner more fully explained hereinafter.

The opening of the front contact 32 of the track relay 4 opens both the 45 degree and the 90 degree control circuits of the semaphore signal S, thus causing the semaphore arm of the signal S to gravitate to the zero degree or danger position, consequently interrupting the circuit at the clearing circuit controller.

Assume now that the train proceeds into

the block J. The track relay 4¹ is deenergized, thereby opening its front contacts and putting the signal S¹ to stop in the same manner as heretofore explained with respect to the block I. Either the opening of front contact 13¹ or of the line circuit controller actuated by the semaphore signal S¹ interrupts the line circuit to the line relay 11 at the entrance of block I. When the train in question passes out of the block I, the track relay 4 is again energized, thereby closing its four front contacts.

The closure of front contact 41 completes the checking circuit which may be traced as follows:—Starting at the terminal P of the battery, checking circuit controller 5—6, wire 42, front contact 41 of track relay 4, wires 43 and 28, one coil 17 of the induction element L, wires 27 and 26, winding of check relay 19, wire 25, one coil of transmitting element T, and wires 24 and 44 to the terminal N of the battery; and another circuit portion in multiple with this latter circuit starting at wire 29, through the other coil 17 of the induction element L, wires 20 and 21, winding of the check relay 18, wire 22, through the other coil of the transmitting track element T, and wires 24 and 44 to the terminal N of the battery.

If both of these checking circuits are intact both of the checking relays 18 and 19 will be energized, thus completing the following circuit for initiating the clearing of the semaphore arm of the signal S to its 45 degree position. This circuit may be traced as follows:—From the terminal P of the battery, front contact 45 of check relay 18, wire 46, front contact 47 of other check relay 19, wire 48, wire 31, front contact 32 of track relay, and thence as in the 45 degree control circuit of the signal S, hereinbefore traced.

During the movement of the signal arm toward its 45 degree position, its initial clearing or operating circuit will be interrupted when the signal arm arrives at the angle α (say 35 degrees), because the checking circuit will be interrupted by the checking circuit controller 5—6, and this in turn causes the checking relays 18 and 19 to drop and open the initial clearing circuit for signal S at their front contacts 45 and 47. When the semaphore of signal S reaches this 35 degree position, or slightly before that position, if desired, the clearing circuit controller 7—8 is closed, whereupon the regular 45 degree control circuit hereinbefore traced is established and the semaphore is operated in the usual way up to its 45 degree position and held there, it being remembered that a train has been assumed to be in the block J, so that the signal can not be operated to its 90 degree position, because the line circuit for line relay 11 is broken both at the contacts 13¹ of the track relay 4¹ and also at the circuit controller 9¹—10¹.

Assume now that the train in question has continued to move in the same direction and passes out of the block J, the track relay 4¹ will again be energized and its front contacts closed, thereby actuating the semaphore arm of the signal S¹ to its 45 degree position in the same manner as heretofore explained in connection with the signal S at the entrance of the block I. Under these conditions the line circuit controller of the signal S¹ is in its closed position, and the line circuit to the line relay adjacent the entrance of the block I will again be energized, thus causing the semaphore signal S to be actuated to its 90 degree position.

It is thus seen that during the passage of each train the continuity of the loop circuit connecting the induction element L with the sending element T will be checked, and if this loop circuit should be open at any point in either of the branches of the checking circuits, one or the other of the checking relays 18 or 19 would not be energized; and therefore the semaphore signal S adjacent thereto can not again assume its caution or its clear position, because the current necessary to start the semaphore from its zero degree position must pass through the front contacts 45 and 47 of both of the checking relays; and if one or the other of these relays is deenergized, this circuit will be open. In this event, since the semaphore signal at the entrance of the block I can not assume any other than its danger position, although the track relay of this block may be picked up, the line circuit to the line relay at the entrance of the block H will be open at the line circuit controller of the block I; and therefore the signal at the entrance of the block H will assume its caution position and open the shunting circuit around the corresponding generating track element, thus putting the track elements of the block H in their operative condition and slowing down or stopping each train coming into the block H until the damaged or interrupted loop circuit of the track elements of the block I has been repaired. In other words, the integrity of this loop circuit is checked each time a train passes, and unless the loop circuit is intact and in the proper condition to protect that train, the next following train is automatically slowed down or stopped in the next block in the rear, and in passing the defective track elements and entering their block, this following train must pass a danger signal and proceed in accordance with the rules and regulations commonly enforced.

In short, in case of breakage or injury of the loop circuit at any time, each train is automatically compelled to stop or reduce speed, perhaps sooner than necessary, before it can reach a train that would otherwise be protected by the defective track elements. It will be observed that this check-

80

85

90

95

100

105

110

115

120

125

130

ing operation is done when needed, that is, when a train passes and requires protection; and consequently, while the loop circuit in question might conceivably break down at any time, it is really not necessary, in a sense, to do anything until the track elements in question are needed to protect a train.

Also, it will be noted that the checking operation does not take place until the rear end of the passing train has cleared the corresponding block. For example, the checking of the loop circuit for the track elements L and T does not take place until the train has passed out of block I. For this reason the checking system may be said to perform the desired function at the time it is likely to be most needed, that is, after the passage of a train that may, on account of dragging equipment or its vibration, cause the breaking down of the loop circuit.

It is noted here that the arrangement above described for automatically checking up the integrity of the loop circuit for the track elements L and T, and governing trains on the side of safety in case of failure of such circuit, is not limited in its application to the automatic detection of failure of this particular circuit in a system of the specific type described; and it should be understood that this automatic checking arrangement is susceptible, by merely making simple changes in circuit connections, of adaptation to the detection of failure of any circuit in a train control or block signal system.

Structure of Fig. 2.—In Fig. 2 has been illustrated in a simplified manner one arrangement of devices and circuits whereby a controlling influence may be received from the track devices illustrated in Fig. 1; and for the purpose of simplifying the description, the most essential parts of the track devices only have been shown.

Various types of cab signaling or brake control apparatus may be controlled by these controlling influences; and since the particular character of this apparatus forms no part of the present invention, and is not material to operation of the invention, a simple type of train control device K has been illustrated in the form of an electro-pneumatic valve which may be used to vent the train pipe directly, and shut off the power in any suitable manner, or which may be used to control other train control devices which may be governed by the speed of the train, the pressure in the brake pipe, the position of the train in the block, and other factors entering into the desired control of the train. This device K is assumed to be provided with an air valve having stick features, that is, one that has been designed to remain open after it has once been opened until a certain pressure reduction has been made. On account of this stick feature, the desired prolongation of action may be obtained even though the in-

fluence and opening of the relay R is only fleeting or momentary. Thus, without employing a stick relay or stick contacts on the electro-pneumatic valve, the use of which would necessitate for usual practical working conditions the provision of some sort of a manual or automatic reset, a valve with such stick feature may be controlled by a momentary impulse, and although only momentarily deenergized, will remain open and vent the train pipe or associated part of the air brake system, until the desired reduction in pressure has been made to cause an effective brake application, whereupon the valve is automatically reseated. It should be understood that such an electro-pneumatic valve to constitute a suitable train control device has been selected to illustrate the nature and mode of operation of the present invention in its simplest aspect, and that the invention is not restricted in its use to the control of such a valve, but may be advantageously employed for controlling the operation of any suitable train governing mechanism.

This train control device K may be actuated by a controlling influence directly, but it is preferably controlled by a control relay R which has been illustrated as governed in turn by a well-known thermionic amplifier or audion shown diagrammatically. This audion has the filament 50, grid 51, and plate 52.

The influence receiving devices of the train control apparatus illustrated comprises a field or primary car element F disposed cross-wise of the vehicle and in cooperative relation with the generating or induction element L at the same time when the receiving or detecting car element D is disposed over the sending or transmitting track element T.

This field or primary element F comprises a U-shaped core of magnetic material, preferably laminated, having enlarged pole pieces and provided with coils 53 on each up-standing portion of the U-shaped core, these coils 53 being wound and connected so that a current flowing therethrough will set up magneto-motive-force in the core in the same direction. The coils of the field or primary car element F have been illustrated as being energized by the batteries B and C and connected in series to the train control device K and the front contact 54 of the control relay R.

The receiving or detecting element D comprises a similar core or yoke provided with secondary coils 55 which are wound and connected in series in a manner so that a change of flux through the yoke produces voltages in the same direction, one end of the winding being connected to the positive terminal of the battery B and the other end to the grid 51 of the audion.

Operation of Fig. 2.—Under normal conditions, that is, while the train is traveling

between control points and is not under the influence of the track elements L and T, the parts and circuits of the car equipment are in the condition shown in Fig. 2. The filament 50 is heated to incandescence by current from the battery A. The battery B will send a small amount of current through the coils 55 of the detecting car element D producing a certain potential on the grid 51 of the audion. 5 This potential on the grid 51 of the audion causes a reduction in the plate circuit resistance, thereby causing a plate current of sufficient strength to flow through the control relay R which will close its front contact 54. 10 The coils 53 of the field or primary car element F being energized from the batteries B and C create a downwardly projected field of flux. 15

Assume that a car with the car-carried apparatus in normal conditions approaches the track elements L and T, and that the line relay 11 (see Fig. 2) is deenergized, thereby opening the shunting circuit around the coils 17 of the induction track element L. As the 20 car passes over these track elements in this stopping condition, a sudden change of flux will take place in the induction track element L, due to the passing of the strong magnetic field produced by the car-carried field or 25 primary element F, thus causing the generation of one cycle of alternating E.M.F. in the coils 17 of the induction element L, and establishing a flow of current through the coils of the sending or transmitting element 30 T. Since the receiving or detecting car-carried element D is positioned directly over the sending or transmitting element T at this time, an E.M.F. will be induced in the coils 35 55 of the said receiving element. This E. M. F. generated in the coils 55 of the receiving element seems to be also of a unicyclic nature, being first in one direction and then in the opposite direction. The coils 55 of the receiving element D are preferably connected 40 to the battery B in a manner so that the first portion of this unicyclic E. M. F. is in an opposite direction to the voltage of the battery B, thus reducing the potential on the grid 51 of the audion, thereby reducing the plate 45 current sufficiently to cause the control relay R to drop its armature and deenergize the train control device K, which in turn applies the brakes or imposes some other form of 50 train control. 55

Assume now that the car-carried devices pass over the induction and transmitting track elements L and T with the shunting circuit about the induction element closed. Under these conditions no influence would 60 be transmitted to the coils 55 of the receiving or detecting element D, because the voltage induced in the coils 17 of the generating or induction element L will not send any current through the coils of the transmitting element T, such current going through the

shunting circuit which has a much lower impedance than said coils. Also, this shunt acts as a short circuit, thereby allowing a bucking current to flow which will tend to prevent further change of flux and generation of an E. M. F. in the coils of element L. In any event, there is not produced a current in the coils of the transmitting track element T sufficient to affect the detecting element D and operate relay R, so that the 70 train may pass without receiving a stopping influence. 75

Structure of Fig. 3.—In Fig. 3 there has been illustrated a modified form of train control system employing another scheme of 80 checking the integrity of the closed or loop circuit of the track elements. In this form of the invention, the car-carried devices are substantially the same as those illustrated in Fig. 2, the audion, batteries, control relay R, and train control device K being connected in the same manner as in Fig. 3; but two field or primary elements F and F^a, connected in series and disposed crosswise of the vehicle, and two receiving or detecting elements D and D^a disposed lengthwise of the vehicle and mounted on the outside of the track rails, have been provided instead of one such unit disposed between the track rails as illustrated in the first embodiment 85 of the invention shown in Figs. 1 and 2. 90

The circuits connecting the devices constituting the car equipment are the same as shown and described in connection with Fig. 2, the only difference being that two field elements F and F^a, and two receiving elements D and D^a are employed instead of the single elements illustrated in Fig. 2. 100

The track elements L and T, constructed the same as shown in Figs. 1 and 2, are also duplicated and are disposed crosswise between the track rails and lengthwise outside of the track rails, respectively, the disposition of the several cooperating elements on the car and track being of course selected so that these respective elements pass directly over one another. 105

With respect to the modified trackway circuits for checking the closed loop including the coils of the track elements L and T, it will be understood that the track rails 1 are divided by joints 2 into blocks in the same way as in Fig. 1, and that each of these blocks is provided with a track circuit including a track battery 3 and track relay 4, a signal S, a line relay 11 governed in the same way as the line relay shown in Fig. 1, the control circuit for this line relay being omitted, however, in Fig. 3 to simplify the illustration. The 45 degree and 90 degree control circuits for the signals S are governed in the same way as shown and described in connection with Fig. 1, except that the wire 31 connected to the front contact 32 of the track relay 4 is connected directly to the battery, rather 115 120 125 130

than through the circuit controller 7—8, or the armatures of the checking relays 18 and 19. The way in which the several signals are caused to assume the stop, caution, and clear positions as trains travel over the track 15 will be readily understood from analogy to the explanation in connection with Fig. 1; and since these features are the same, only the track equipment at the entrance to block 20 I has been shown in Fig. 3.

Operated by the signal S are two circuit controllers 56 and 57 which are shown in accordance with the same convention as those illustrated in Fig. 1 and previously described.

25 The circuit controller 56 is closed through a suitable angle between the 90 degree position and near the 45 degree position, for example, from 50 degrees to 90 degrees. The other circuit controller 57 is closed between the zero degree position of the semaphore and a position slightly above the 45 degree position, either the same or a few degrees more than the point at which the circuit controller 56 is closed, so that circuit controller 57 closes 30 before circuit controller 56 opens, and vice versa.

Operation of Fig. 3.—In this modified arrangement, the integrity of the loop circuit for the track elements L and T is checked by 35 making this loop circuit a part of the track circuit for the next block in the rear, so that if there is a break in this loop circuit, the track relay of said block in the rear can not pick up, thereby putting at stop and caution, respectively, two signals and their associated track elements in the rear of the defective track elements. In connection with this modified checking scheme, there is preferably employed an additional insulated joint 58 in 40 one of the track rails at a short distance from the joints 2 at the exit end of the block, this distance being such that a pair of wheels of the car will be between the joints 2 and 58 at the time the car elements F and D come 45 over the track elements L and T.

When the signal S is in clear position and circuit controller 56 is closed, the track battery 3 of the block H supplies current to the track relay of that block over the following circuit:—Commencing at one terminal of the track battery 3, wire 59, coils 17 of track element L^a, wire 60, coils 17 of track element L, wires 61 and 62, circuit controller 56, wires 63 and 64, track rail 1, back through the track 50 relay of block H (not shown), back along the other track rail 1 to insulated joint 58, thence along wire 65, through adjustable resistance 66, wire 67, balancing resistance 68, wire 69, to the other side of the joint 58, short track rail section and wire 70, back to the other terminal of battery 3.

The adjustable resistance 66 in this circuit just traced corresponds to the limiting resistance commonly used in connection with 55 the track battery of track circuits, more par-

ticularly when such batteries are of the potash type or the like, and have low internal resistances, the function and purpose of such limiting resistance being well recognized in the art and requiring no discussion in connection with this invention. It is noted here that the adjustable resistance 66 may be omitted under certain conditions in practice, since the coils 17 of the elements L and L^a included in series with the track battery 3 70 may be utilized to serve the purpose of such limiting resistance. The other balancing resistance 68 is made equal to the combined resistances of the coils 17 of the track elements T and T^a, for reasons that will be pointed out 75 later.

From the foregoing it will be observed that the coils 17 of the elements L and L^a are included in the circuit by which current is normally supplied to the track relay of the block H, so that if there is a break at any time in these coils, or the wires connecting them, this track relay drops, the signal at the entrance to block H goes to stop, and the next signal in the rear is put to caution. In other words, so far as the coils of the elements L and L^a are concerned, this modified checking arrangement provides a continuous check or detection.

With this explanation of the normal condition of the parts and circuits of the track-way equipment of Fig. 3, assume now that a train, equipped as shown in Fig. 3, is in the block H, as shown, and is traveling in the normal direction of traffic indicated by the arrow, and suppose that the block I and also the next block in advance thereof (not shown) are clear or unoccupied. In the first place, the train in question in the block H causes dropping of the track relay of that block in the usual way, the inclusion of the coils 17 of the track elements L and L^a in the track circuit for this block not modifying in any way its usual and well recognized operation. As the train in question advances, and the first pair of wheels passes beyond the insulated joint 58, the resistances 66 and 68 are cut out. When the field elements F and F^a on the car pass over the induction elements L and L^a on the track, an electro-motive-force is induced in the coils 17 of said induction elements in the same manner and for the same reasons previously explained; but this E. M. F. sends current through the shunt provided by wires 62 and 63 and the circuit controller 56, rather than through the coils of the transmitting elements T and T^a, the resistance of such shunt being of course much less than that of the coils of said transmitting elements. Consequently, the transmitting elements T and T^a do not create a magnetic field to influence the receiving elements D and D^a on the car. Also, the current flowing in the coils of the induction elements L and L^a through the 90

low resistance shunt provided by the circuit controller 56 and associated wires, acts in accordance with well-known laws to set up counter-magneto-motive-force opposing the passage of flux from the field elements F and F^a through the cores of said induction elements. In other words, not only is the flow of current through the transmitting elements T and T^a prevented, but also the induced current in the coils of the induction elements is reduced on account of the choking effect caused by including these coils in a closed circuit of low resistance. In any event, the receiving elements D and D^a are not affected under the clear traffic conditions assumed.

Assume now that the train in question advances wholly into the block I. The signal S is caused to assume a stop position, the circuit controller 56 is opened, and the circuit controller 57 is closed. The circuit over which the track battery 3 now delivers current to the track circuit in the block H is as follows:—Commencing at one terminal of battery 3, wire 59, coils 17 of element L^a, wire 60, coils 17 of element L, wires 61 and 71, coils 17 of element T^a, wire 72, coils 17 of element T, wires 73 and 64, track rail 1, through track relay, back over other track rail, wire 65, adjustable resistance 66, wires 67 and 74, circuit controller 57 closed, wires 75 and 69, short track rail section and wire 70, back to the battery 3.

It will be noted that this circuit just traced includes the coils 17 of both the induction elements L and L^a and the transmitting elements T and T^a; or in other words, the track battery 3 must send its current through the same loop circuit connecting said induction and transmitting elements and placing them in condition to influence the apparatus on a passing train. In this way, the integrity of the loop circuit, on which the stopping operation of this particular type of system depends, is automatically checked; and in case there is a break in the coils or their connecting wires, no current will be supplied to the track relay of block H, putting the signal and associated track elements at the entrance to that block at stop, and also the signal next in the rear at caution, with its associated track elements also in the stopping condition. Consequently, in case of failure of the loop circuit following trains are controlled on the side of safety in the same way as previously explained.

It will also be noted that in the circuit just traced, while the coils 17 of the transmitting elements T and T^a have been included in the track circuit, the balancing resistance 68 has been shunted out by closure of circuit controller 57, so that the net resistance in circuit with the track battery 3 remains the same, and the operating characteristics of the track circuit are not altered.

Suppose now that the train in question advances into the block J (not shown) next in advance of the block I. The signal S is operated to the 45 degree or caution position, but the circuit controller 57 remains closed, 70 and the circuit controller 56 is open, so that there is no change in the circuits associated with the track elements of the train control system.

When the signal S is in either the stop or 75 the caution position, circuit controller 56 being open, the coils of the transmitting elements T and T^a and the induction elements L and L^a are connected in series in a loop circuit corresponding to the loop circuit 80 hereinbefore discussed in connection with Fig. 1. The loop circuit in Fig. 3, however, includes the track battery 3, and also the limiting resistance 66, if used, but the resistance 68 is cut out. Suppose that a train, 85 equipped as shown in Fig. 3, approaches the signal S in its caution or stop position before the elements on this train pass over the track elements. A pair of wheels and axle of the train are between the joints 2 and 58 so that the limiting resistance 66 is cut out of the loop circuit, this loop circuit now including only the track battery 3 and the connecting wires in addition to the coils 17 of the induction and transmitting elements. A stopping influence is produced on the passing car 90 under these conditions in the same way as previously explained. The field elements F and F^a induce a current in the coils of the induction elements L and L^a which passes 100 through the coils of the transmitting elements T and T^a and creates fields of flux which act upon the receiving elements D and D^a to cause deenergization of the relay R and the train control device K.

In connection with the operation of the modified arrangement shown in Fig. 3, it will be noted that, when the track elements are in the active stopping condition the transmitting elements T and T^a are magnetized 110 to a degree by current from the track battery 3; and to utilize to the best advantage this energization of said coils that exists independently of the induction of current from the source of flux carried on the car, the several coils and connections are preferably selected so that the first half wave produced in the coils of the induction elements L and L^a is in a direction to assist the voltage of battery 3 to send current through the coils of 115 the transmitting elements T and T^a, the car equipment being correspondingly designed to employ this first half wave to drop the relay. It should be understood, however, that other combinations of connections may be 120 employed, if desired.

With regard to the checking operation of the modification of Fig. 3, it will be noted that failure of the coils of the induction elements L and L^a at any time will be mani- 125

fested by putting to stop the next signal in the rear. The coils of the transmitting elements T and T^a, however, are not included in the circuit normally supplying current to the track circuit, so that there may be a failure of these coils at certain times without causing stopping of the next train; but it will be observed that, so long as there is a train in the block I, for example, or in the next block in advance thereof, the integrity of the loop circuit through the coils of the transmitting elements T and T^a is checked, and in case of failure, following trains will be slowed down or stopped. Thus, the complete loop circuit is always under check at the time it may be needed to protect a train in the corresponding block or the next block in advance; and although the modified checking arrangement differs from that shown in Fig. 1, since it does not leave signals permanently in the stopping condition in case of failure, each and every train will be slowed down and stopped in case there is a train needing the protection of track elements that have a defective loop circuit.

Structure of Fig. 4.—In Fig. 4 another modified form of the car apparatus illustrated in Fig. 2 has been shown. The main difference between this form and that of Fig. 2 is the omission of the thermionic amplifier, and the relay R is controlled directly from the coils 55 of the receiving element D. The other car-carried devices are the same as those heretofore described and are placed substantially the same as those in Fig. 2, with the exception of the batteries. In Fig. 4 one battery C¹ is used for the circuit through the coils 55 of the receiving element, and another battery B¹ for the coils 53 of the field element. The circuit through the coils 55 of the receiving element D may be traced as follows:—Beginning at the battery C¹, wire 76, winding of control relay R, wire 77, coils 55 of the receiving car element, and wire 78, back to the battery. The circuit through the coils 53 of the field element F may be traced as follows:—Beginning at the battery B¹, wire 79, coils 53 of the field element, wire 80, front contact 54 of the control relay R, wire 81, winding of the train control device K, and wire 82, back to the battery. The operation of this form of the invention is analogous to that illustrated in Fig. 2 and detail description is believed unnecessary.

Structure of Fig. 5.—In Fig. 5 has been illustrated another form of car apparatus. The field element F and the circuit through its windings 53 is identical to that illustrated in Fig. 4 and is given like reference characters. The receiving element D¹ of this modified construction comprises two flux collecting members or poles 83—84, having enlarged pole pieces. These enlarged pole pieces are arranged to be in communicating relation with the two pole pieces of a transmitting

track element T as heretofore described. The upper ends of said members 83 and 84 are separated by an air gap; and pivotally mounted on the member 83 and disposed to bridge this air gap is a soft iron armature 85 biased to an open position by a spring 86. This armature 85 carries an insulated contact spring 87, which, under normal conditions, bridges stationary contacts (shown conventionally as arrows) to close the following circuit:—Beginning at the battery C¹, wire 88, winding of control relay R, wire 89, stationary contacts and contact spring 87, and wire 90, back to the battery.

Operation of Fig. 5.—Assume a train, equipped with the car-carried apparatus illustrated in Fig. 5, is moving between two control points of a track equipped with track devices as illustrated in Fig. 2 of the drawings. Under these conditions, the control relay R, the train control device K, and the coils 53 of the field element F are energized. When the train passes over the track elements L and T illustrated in Fig. 2 in their active stopping condition, a current is caused to flow in the loop circuit connecting the track elements L and T, in the same way as before described, thus creating a field of flux above the sending or transmitting track element T which passes through the car-carried receiving or detecting element D¹, thereby attracting the armature 85 and opening the circuit to the control relay R, which in turn drops its armature 54 and breaks the circuit through the train control device K, bringing the train to a stop or imposing some other form of train control.

Structure of Fig. 6.—In Fig. 6 there has been illustrated still another form of car-carried apparatus. In this form the coils 53 of the field element F are energized by a battery B¹ in series with the train control device K, in substantially the same manner as illustrated in Figs. 4 and 5. This circuit can be readily traced on the drawings.

The receiving or detecting element D² of this embodiment comprises a core of general H-shape, the bottom legs being provided with enlarged pole pieces, while the top legs have inwardly extending projections. On the cross bar 91 of said core is a coil 92 which is constantly energized from a battery or other source of current 93, so as to make one leg a north and the other a south pole of a magnet, as indicated, for example, in Fig. 6. To one of these inwardly projections at the upper part of said core is pivotally supported an armature 94 which is normally attracted in opposition to a spring 95 by the magnetism passing through the cross-bar, projections and the armature. A contact finger 96 is mechanically connected to but insulated from the armature 94 by insulated studs; and when the armature 94 is in its normal attracted position, this contact finger bridges a pair of

stationary contacts (shown as arrows) in circuit with the train control device K. The number of turns of the coil 92 and the strength of its energizing battery 93 are selected and proportioned, with due regard to the reluctance of the magnetic circuits under normal conditions, so that the flux produced by this coil and passing through the armature 94 will be approximately that required to hold the armature in its attracted position against residual stops (not shown) in opposition to the spring 95 with a suitable margin to avoid premature opening of the armature due to vibration or the influence of track rails or other magnetic bodies along the track. Other factors determining the magneto-motive-force to be exerted by the coil 92 should, however, be taken into consideration in practice, as will be evident as the function and mode of operation of this form of car apparatus is further explained. It is noted here that the cross section of the cross bar 91 is selected so that this bar will be magnetically saturated by the flux produced by the coil 92, so that in case of a change in the reluctance of the partial magnetic circuits supplied with flux from the coil 92, the total amount of flux will not materially increase and will divide itself in accordance with the reluctance of these magnetic circuits, as more fully explained hereinafter.

Operation of Fig. 6.—Assume the track equipment illustrated in Fig. 2 of the drawings to be in its danger condition, that is, with the coils of the track elements L and T in a closed and unshunted circuit; and further that a car, equipped with the apparatus illustrated in Fig. 6 in its normal condition illustrated is approaching the track elements L and T of Fig. 2 in this danger condition.

As the car elements F and D² pass over the track elements L and T, a current will be set up in the loop circuit by the change of flux produced in the coils 17 of the induction element L when the field element F passes thereover.

The E. M. F. induced in the coils 17 of the induction element L will be one alternating cycle, one wave or half cycle being in one direction, and the other wave in the other direction. This induced voltage in turn sends a current through the coils 17 of the transmitting track element T (Fig. 2), and this current will create a field of flux above said element first in one direction and then in the other. Putting it another way, the pole pieces of the transmitting track element will be alternately north and south. As the receiving or detecting element D² of Fig. 6 passes through this magnetic field, the magneto-motive-force produced by said transmitting element may assist or oppose that of the energized coil 92. If the magneto-motive-force

of the transmitting element and that produced by the coil 92 of the receiving element act together, some of the flux normally passing through the armature 94 will be diverted through the core of the transmitting element. On the other hand, if the magneto-motive-force of the transmitting track element opposes that of the energized coil 92, they both act together to send more flux through the armature 94 and hold it more strongly in its normal attracted position.

The several parts are selected and proportioned so that the flux through the armature 94 is reduced sufficiently to allow the spring 95 to move said armature away from the attracted position and interrupt the circuit through the train control device K at the time these magneto-motive-forces are acting in the same direction. In this connection it should be remembered that the cross bar 91 is made of such cross section as to be substantially saturated by the flux produced by the energizing coil 92. Consequently, the transmitting track element T, with its assisting magneto-motive-force, when it comes into communication with the partial magnetic circuit through the cross bar 91 and lower legs of the element D², necessarily causes a reduction in flux through the armature 94, because the cross bar 91, being saturated, does not allow any more than a certain sum total of flux to pass, with the result that when part of this flux is carried down through the track element, such flux is taken out of the armature.

The spacing of the field element F and the receiving element D² on the car, with relation to the spacing of the induction element L and transmitting element T on the track, may be selected such that the legs of the receiving element D² are directly over the pole pieces of the transmitting element T at the instant when the magneto-motive-force or flux of said transmitting element is at a maximum in one direction or the other, or at any point between. Also, this relative spacing may be such that the receiving element D² will come over the transmitting element T at the time of one wave, either the first or second wave of complete cycle, and will be beyond the influence of said transmitting element for the other wave of such cycle. The spacing of the car elements may, therefore, be selected or adjusted to obtain the most advantageous effect for the operation of the armature 94 to conform with any particular working conditions. It is considered preferable to have this spacing such that the receiving element D² will be under the influence of only one wave which is the operating wave, that is, the one that causes a diversion of flux from the armature 94 through the transmitting track element.

One important characteristic of the modified construction shown in Fig. 6 is that the

flux normally passing through the armature 94 may be reduced by the action of the transmitting element T to a greater extent under ordinary conditions than could be obtained by merely changing reluctance by a track element constituting an inert mass of iron. In the arrangement of this invention, the magneto-motive-force momentarily created by the transmitting element T acts to pull or suck down, so to speak, the flux produced by the energized winding 92, and taking away a large proportion, if not substantially all, of the flux that this energized coil normally sends through said armature. Bridging the pole pieces of the receiving element D² by a magnetic body, however, would merely serve to lower the reluctance of the partial circuit through the lower legs, and while this arrangement would deprive the armature 94 of some of its flux, there would still be ordinarily an appreciable amount of flux through this armature, inasmuch as the flux would divide inversely in proportion to the reluctance of the two multiple circuits set up.

Structure of Fig. 7.—In Fig. 7 there has been illustrated a form of car-carried apparatus for controlling the movement of a train, which embodies a modified form of field or primary devices which, although applicable to each of the foregoing car-carried systems, has for convenience been illustrated in connection with the particular system shown in Fig. 4. Since the wiring diagram and the general arrangement of devices is the same as that of Fig. 4, the same reference characters have been used for corresponding parts. Instead of a single field element F, two such elements have been provided. These elements F and F¹ are supported on a vehicle in a manner to first induce a field of flux in one direction in an induction track element L, and then in the other in a manner that the flux will change rapidly from a maximum in one direction to a maximum in the other direction, whereby a current is induced in the loop circuit track devices of a much greater effective value than if only one field element is used. Although these field elements may be disposed in any relation to the trackway as illustrated by the cooperating induction track element that has been illustrated in each of Figs. 8 to 17, they have for convenience been shown disposed cross-wise of the vehicle. The field elements F and F¹ are provided with coils which are connected in series in a manner so that they act together, that is, the magneto-motive-forces induced in the element due to current flowing through these coils will be in the same direction; and two elements are further connected in series in a manner so that the polarity of adjacent ends of the field elements are opposite, and for convenience the left forward and the right rearward poles of these field elements will be considered to be a north pole.

Operation of Fig. 7.—Assume that the trackway devices illustrated in Fig. 2 are in the danger condition, that is, the line relay 11 is deenergized, thus opening the shunt circuit and thereby putting the coils of the track elements L and T in an unshunted closed circuit. Assume further that a train is approaching from the left equipped with the car-carried apparatus illustrated in Fig. 7 in its normal condition as illustrated.

When the first field element F passes over the induction track element L, the flux through this element L will change from zero to a certain maximum value from the time the field element F gets into the range of action, to the time it gets directly over the induction element, thus generating a voltage in the winding of the induction element L as illustrated by the wave X in Fig. 7-A. At this position of the field element, that is, when it is directly over the track element, very little leakage of flux between the field elements F and F¹ is present. As the field element F recedes from the induction element L the flux through the induction element decreases to zero very rapidly. This is believed to be due to the increase of reluctance through the magnetic circuit comprising the elements F and L, aided by the increase of leakage between the field elements, while the field elements straddle the induction element. This leakage, or diversion of flux, from the core of the induction element L is assisted by the fact that the alternative path through the field element F¹ includes a helping source of magneto-motive-force, the legs of said field elements being of opposite polarity as previously explained. This rapid decrease of flux produces a voltage in the opposite direction to that of the first wave X, for reasons well-known to those skilled in the art.

At the point of movement when the field elements are spaced equal distances from the induction element L, the field of flux through the induction element is substantially zero, but the voltage generated at this point is not necessarily zero, since the rate of change of flux at this point may be high, and in passing through this point the flux changes in direction since the legs of the field elements F and F¹ are of opposite magnetic polarity. Consequently, there is the greatest rate of change of flux at this point, and the induced E. M. F. is a maximum.

As the vehicle advances from the point just mentioned, the flux through the induction element increases in the opposite direction until the field element F comes directly over the induction element L, at which point the flux through the element L is a maximum, the rate of change small and the voltage low. This completes the lower wave Y of the voltage curve shown in Fig. 7-A. As the field element F¹ recedes from the track element L the flux through the track element gradually

changes to zero, making the wave Z in Fig. 7-A.

Fig. 7-A is intended purely for purposes of explanation, to illustrate how the lower voltage wave Y, which is generated by the combined action, so to speak, of the two field elements F and F¹ has a higher maximum value. It should be understood, however, that the wave forms are merely illustrative and are not intended to be quantitatively accurate, it being readily appreciated that the exact values of induced voltage will in practice vary considerably, depending upon the size of parts and other features of design, together with a number of other variable factors.

It should also be understood that the foregoing explanation of mode of operation is based upon theoretical assumptions, which may or may not be invariably true in the practical application of the invention, on account of variations of design and other conditions.

Besides the advantage of generating a much larger current in the track loop circuit by the employment of two field elements instead of one, a still other desirable characteristic is present. If a single field element is carried crosswise of the vehicle and is energized by a direct current, there is a tendency for it to permanently magnetize crossing rails and similar magnetic bodies which have sufficient permanence (hold their magnetism); and when such field element repeatedly passes over such bodies, they will become permanent magnets. These magnetized bodies or crossing rails may under certain adverse circumstances cause a false control influence to be transmitted to the detecting element. If two field elements trailing each other having their polarities opposite are used, as has just been illustrated, any residual magnetism set up by the passage of one of the field elements will be killed by the passage of the other field element, and the maximum magnetism that will be set up at any time will be the residual magnetism left by the passage of a single element. Such residual will be very feeble and thus harmless, as compared with the magnetism produced when a single field element passes over such bodies repeatedly.

Checking of car-carried devices.—It should be noted that every car-carried equipment illustrated is constructed along the normally closed circuit principle, or is self-checking. In Figs. 2 and 3 the failure of a sufficient current supply to the filament 50 of the audion will reduce the plate current which in turn will drop the armature of the control relay R, and stop the train as heretofore explained. The same is true of insufficient potential on the grid circuit. If either the circuit through the control relay R, or the circuit through the train control device K should be reduced or interrupted altogether, the train will be stopped or otherwise controlled. In Fig. 6, if

the current in the winding 92 on the cross bar 91 should be sufficiently reduced or altogether interrupted, the armature 94 will be pulled away from the extending projections by the spring 95, thereby opening the circuit 70 to the train control device K and applying the brakes or controlling the train in some other suitable manner.

Disposition of track elements.—On account of certain variable conditions, such as the variation in the diameter of the car wheels due to wear, and other variable quantities entering into the operation of inductive transmitting systems of this kind, a certain amount of air gap between the track and car elements 75 is required in any event; and if the elements are located outside of the track rails, this is the only clearance allowance which needs to be taken into consideration. If, however, these elements are located between the track 80 rails, other clearance factors enter into the problem and larger air gaps must in some cases be provided. For instance, if the track elements are placed between the rails, certain railroads require them to be placed several 85 inches below the top of the rail, in order that they will clear the flangers of snow plows which extend down below the top of the rails. Certain of these railroads will, however, permit these track elements to be placed level 90 with the track if their poles are substantially in the middle between the rails, because the snow plow flangers may be notched at this point to clear the track elements and still take out as much snow from between the rails 95 as is necessary.

In connection with these devices still another question must be taken into consideration, namely, the spacing of the car-carried elements with respect to the spacing of the trackway elements, which should be such that the impulse received by the detecting element will be the strongest, all other conditions remaining the same. In this connection it should be noted that in each inductive type 105 of car apparatus, shown in Figs. 2, 3, 4 and 7, the rate of change of flux in the detecting element D is dependent on both the rate of change of flux in the transmitting element T and the velocity at which the element D 110 passes over the element T. The detecting elements D¹ and D², shown in Figs. 5 and 6, depend on the amount of flux rather than on the rate of change of flux, and therefore the car and track elements are so spaced relatively that the flux produced by the transmitting element T will be most effective when the detecting element D is directly over the same. Still another condition regarding the spacing of the car elements with respect to the 115 track elements must be taken into consideration, especially in regard to the car-carried devices illustrated in Fig. 6. In this form of detecting element, the operation does not depend merely on the amount of flux, but also 120 125 130

upon its polarity; and therefore the spacing of the elements and the connection of the several coils to the batteries and to each other, will be so chosen that the detecting element ⁶D² will be over the transmitting element T when the flux induced therein is most effective and also in the proper direction. If two field elements, as illustrated in Fig. 7, are employed in connection with anyone of the ¹⁰car-carried systems illustrated, a still further consideration must be given to the relative spacing of car and track elements. In this event, the elements will be so spaced that the magnetism due to the largest wave of the ¹⁵curve X, Y, Z will be in the proper relation to the detecting element D, such relation to the moving detecting element depending upon whether the particular detecting element is responsive to rate of change of flux or to the ²⁰amount of flux, as heretofore explained.

In each of the Figs. 8 to 17, inclusive, an arrangement or disposition of the track elements has been illustrated to show how they may be arranged to suit particular operating ²⁵conditions. Two track rails 97 and 98 have been shown with respect to which an inductive or generating element L and a transmitting or sending element T has been illustrated. Certain of these elements have been ³⁰designated T and L on the drawings; but it should be understood that either element may be used for either function. Although various arrangements of placing of the track elements with respect to the track rails have ³⁵been illustrated, it should be borne in mind that these are merely illustrative, and that all possible arrangements have not been shown. Since these figures are self-explanatory, no ⁴⁰further description thereof is believed necessary.

An inductive apparatus for communicating control influences for automatic train control systems has thus been provided in which an inert track device entirely different from anything along the trackway is used, therefore making it impossible to falsely transmit a controlling influence by foreign structure along the trackway, such as magnetic material, and at the same time deriving all of the energy used for such inductive transmission from the moving vehicle itself, rather than from a source of electrical energy supply along the trackway. Since the integrity of a circuit is necessary for ⁴⁵transmitting this control influence, the failure of which might prevent the transmission of an influence at a time when one is to be transmitted, if desired, a checking system to check the integrity of the circuit may be ⁵⁰added; and several forms of such a checking system have been provided.

While I have explained the nature of my invention by discussing the construction and mode of operation of certain specific forms ⁶⁵of apparatus, it will be evident that the in-

vention may be considered in the broader aspect of a novel method of transmitting influences from the trackway to moving vehicles, adaptable to train control systems.

While I have described my invention in connection with a specific type of block signal system, the invention is more general in its application. The particular construction shown and described may be modified and adapted in many respects to suit the particular working conditions; and I desire to have it understood that the illustration and description does not exhaust the adaptations and modifications of the means, and its functions constituting this invention.

What I claim is:—

1. In an automatic train control system; the combination of vehicle carried apparatus comprising, a thermionic device having a plate circuit, a grid circuit, a filament circuit, an electro-responsive device connected in said plate circuit, an influence receiving coil connected in said grid circuit, a magnetic core having a normally energized winding thereon for producing a magnetic flux in said core; and of trackway apparatus including a pair of trackway elements each having a coil thereon and so positioned with respect to the trackway that one element cooperates with said influence receiving element when the other cooperates with said flux producing coil, and a circuit connecting the coils of said trackway elements in series when a control influence should be transmitted.

2. Trackway apparatus for communicating control influences from one car-carried device to another under predetermined traffic conditions ahead comprising, a pair of cores each having two upstanding legs and disposed along the trackway so that the legs extend upwardly, a coil on each of said cores, and means for effectively connecting said coils in series under predetermined traffic conditions ahead, said cores being positioned along the trackway so that the legs of each of said cores fall in different planes.

3. Trackway apparatus for communicating control influences from one car-carried device to another under predetermined traffic conditions ahead comprising, a pair of cores each having two upstanding legs and disposed along the trackway so that the legs extend upwardly, a coil on each of said cores, and means for effectively connecting said coils in series under predetermined traffic conditions ahead, said cores being positioned in different paths along the trackway and being so placed in the plane of the trackway that the legs of each of said elements are disposed in different vertical planes.

4. In an automatic train control system, the combination of car-carried train control devices, a track device including a deenergized closed circuit for communicating control influences to said car-carried devices,

one of said car-carried devices inducing a voltage in said circuit upon passage of said car-carried devices over said trackway devices, and the other of said car-carried devices detecting the flow of current in said circuit, and means for checking the integrity of said circuit by each passing train to safeguard a following train.

5. In an automatic train control system, a pair of track devices each including a core having a coil thereon, said coils being connected by a local closed circuit for transmitting a danger control influence to a moving train, and means for transmitting a danger control influence to the track device at the next control point in the rear if the continuity of the circuit is interrupted.

6. In an automatic train control system; the combination of a trackway divided into blocks by insulating joints, a signal at the entrance to each block, influence communicating means at the entrance to each block for transmitting inductive control influences to a moving vehicle and including a coil, means for preventing said signal from assuming the proceed position when the circuit including the coil of said influence communicating means is open; and car-carried apparatus controlled in accordance with whether the circuit including said coil is open or closed.

7. A system for transmitting controlling influences from the trackway to moving vehicles, in which a flux responsive detecting device on the vehicle is actuated by cooperating means partly on the vehicle and partly on the track and including a source of magneto-motive-force on the vehicle, said source of magnetic-motive-force and said detecting device having differently disposed flux paths with relation to the trackway.

8. Trackway apparatus for automatic train control systems comprising, a railway track divided into blocks, an inductive influence communicating element for communicating inductive control influences from the trackway to a vehicle including a core of magnetic material having a winding thereon at the entrance to each block, a wayside signal located near the entrance to each block for indicating traffic conditions ahead, a circuit including said winding closed under predetermined traffic conditions ahead, and means for preventing said signal from assuming the proceed position when said circuit is open.

9. In a train control system of the character described, a flux responsive device on the vehicle, a source of magneto-motive-force on the vehicle, and trackway means governed by said magneto-motive-force for influencing said flux responsive device, said source and flux responsive device having flux paths disposed differently with respect to the trackway.

10. Trackway apparatus for block signal-

ing and train control systems comprising, an influence communicating track element for transmitting control influences inductively from the trackway to suitable vehicle carried influence receiving means including a core having a coil thereon, a wayside signal, a relay, a circuit including said coil and said relay, and a circuit controlled by said relay for preventing said signal from assuming the proceed condition if the circuit including said coil and relay is open at a time when it should be closed.

11. Trackway apparatus for block signaling and train control systems comprising, an influence communicating track element for transmitting control influences inductively from the trackway to suitable vehicle carried influence receiving means including a core having a coil thereon, a wayside signal, a circuit including said coil, and means for preventing said signal from assuming the proceed condition if the circuit including said coil is open.

12. Trackway apparatus for block signaling and train control systems comprising; an influence communicating track element for transmitting control influences inductively from the trackway to suitable vehicle carried influence receiving means including a core having a coil thereon, a wayside signal; a circuit including said coil, a relay and a source of energy; a circuit for causing said signal to assume the proceed condition including a front contact of said relay, whereby said signal cannot assume the proceed condition unless the circuit including said coil is intact and said relay assumes its energized position.

13. In an automatic train control system; the combination of car-carried apparatus comprising, a normally energized inductive influence transmitting element, an inductive influence receiving element of magnetic material having an influence receiving coil thereon, a thermionic device connected to said influence receiving coil, an electro-responsive device connected to said thermionic device; and of trackway apparatus for inductively coupling said influence transmitting element to said influence receiving element including trackway devices effectively connected in series under predetermined traffic conditions ahead, and means for checking the integrity of the circuit including the two trackway devices in series.

14. A train control system comprising, a car-carried magnetic element having a normally energized winding thereon for producing a magnetic flux in such element, another car-carried magnetic element having an influence receiving winding thereon, trackway means including a circuit in which current is induced by the flux of said first mentioned element and adapted in the stopping condition to create a magnetic field influenc-

- ing the influence receiving winding, and means including a train control device and electrical circuits for controlling the train when said influence receiving winding is influenced, said last mentioned means and said trackway means being constructed so that accidental interruption of any of said circuits will cause an actuation of said train control device.
15. Trackway apparatus for block signaling and train control systems comprising; a railway track divided into blocks each having a track relay; an influence communicating track element for transmitting control influences inductively from the trackway to suitable vehicle carried influence receiving means including a core having a coil thereon located at the entrance to each block; a wayside signal; a circuit including said coil, a 20 check relay and a source of energy; a line relay controlled by said track relay; and a circuit for causing said signal to assume the proceed condition including a front contact of said check relay and a front contact of said line relay in series.
16. Trackway apparatus for automatic block signal and train control systems comprising, an influence communicating track element for transmitting control influences inductively from the trackway to suitable vehicle carried influence receiving means including a core having two coils thereon, a wayside signal, two circuits in multiple each including one of said coils, and means for preventing said signal from assuming the proceed condition if either of said two circuits are opened.
17. An automatic train control system comprising; car-carried apparatus including a car element of magnetic material having an influence receiving coil thereon, and an electro-responsive device actuated upon the reception of a control influence by said influence receiving coil; and trackway apparatus for transmitting control influence to said influence receiving coil including a track element of magnetic material having a coil thereon connected in series with the usual track circuit, and means for shunting said last mentioned coil under predetermined traffic conditions ahead.
18. A trackway apparatus for automatic block signaling and train control systems comprising, a railway track divided into blocks each having a closed track circuit, an inductive influence communicating device including a core of magnetic material having a winding thereon located near the entrance to each block, a wayside signal at the entrance to each block, and a control circuit for said signal, closed only if said winding is intact, for causing said signal to change its indication from stop to caution or proceed.
19. A train control system comprising, a normally energized electro-responsive de-
- vice, a normally energized train control appliance controlled by said device, a car-carried influence receiving element having a coil thereon in which a current flows to maintain said electro-responsive device energized, whereby the reception of a control influence causes deenergization of said device, an influence transmitting element including a normally energized field coil connected in series with said train control appliance, and trackway apparatus for inductively coupling said influence transmitting element to said influence receiving element under predetermined traffic conditions ahead.
20. A trackway apparatus for automatic block signaling and train control systems comprising, a railway track divided into blocks each having a closed track circuit, an inductive influence communicating device including a core of magnetic material having a winding thereon located near the entrance to each block, a wayside signal at the entrance to each block, and means effective only if current traverses said winding for changing the indication of said signal from stop to a more favorable indication after once caused to give its stop indication by the passage of a train.
21. Trackway apparatus for automatic train control systems of the type employing closed track circuits each having a track relay comprising, a trackway device including a core of magnetic material, a coil associated with said core, a wayside signal controlled by such track circuits to give indications corresponding to traffic conditions ahead, and means effective if said coil is accidentally open-circuited to prevent said signal from again indicating favorable traffic conditions regardless of actual traffic conditions existing ahead so long as said coil remains open circuited.
22. Trackway apparatus for automatic train control systems of the type employing closed track circuits each having a track relay comprising, a trackway device including a core of magnetic material, a coil associated with said core, a check relay in series with said coil, a source of energy for energizing said coil, a circuit which if energized causes said signal to assume a favorable traffic indicating condition, said circuit including a front contact of said check relay and a source of energy, whereby said signal will indicate unfavorable traffic conditions regardless of actual traffic conditions existing ahead if the continuity of said coil is accidentally broken and the signal has thereafter indicated adverse traffic conditions.
23. Trackway apparatus for automatic train control systems of the type employing closed track circuits each having a track relay comprising; a trackway inductive influence communicating device including a core of magnetic material; a coil associated with

- said core; a wayside signal adapted to indicate clear, caution or danger depending on traffic conditions in the block at the entrance to which it is located and traffic conditions in 5 the next block in advance thereof; a partial circuit which if closed permits said signal to assume a clear indicating condition; another partial circuit which if closed permits said signal to continue to indicate clear traffic 10 conditions if it has once assumed such indication condition and traffic conditions remain clear; said first mentioned partial circuit being closed only if said coil is not open-circuited; whereby accidental breakage of the 15 continuity of said coil manifests itself by an unfavorable traffic indicating condition of said signal, in spite of favorable traffic conditions ahead, if said signal has once assumed an unfavorable traffic indicating 20 condition since said coil was accidentally open-circuited.
24. In an automatic train control system, the combination of car-carried apparatus for 25 restricting the movement of trains in response to control influences transmitted inductively from the trackway; and of trackway apparatus comprising, an inductive influence transmitting device for transmitting control influences to a moving train under 30 adverse traffic conditions ahead, including a core having a coil thereon; a wayside signal at the entrance to each block; and means effective upon passage of a train for causing the next signal in the rear of the influence 35 transmitting device to indicate caution when the coil of said device is accidentally opened in spite of the existence of more favorable traffic conditions ahead.
25. An automatic train control and wayside signalling system for railways having tracks divided into blocks by insulating joints; a closed track circuit for each block including the track rails in series, a track relay and a source of energy; a wayside signal; an 40 inductive influence communicating trackway device including a coil, said coil being at times energized and at times de-energized depending on traffic conditions; and means including a check relay for checking 45 the integrity of said coil upon each passage of a train; said means manifesting a break in the continuity of said coil by a signal indication indicating adverse traffic conditions ahead, in spite of the existence of more favorable 50 traffic conditions ahead.
26. An automatic train control and wayside signalling system for railways having tracks divided into blocks by insulating joints; a closed track circuit for each block 55 including the track rails in series, a track relay and a source of energy; a wayside signal for indicating clear, caution or danger, depending on traffic conditions ahead; an inductive influence communicating trackway device including a coil; said coil being at times 60
- energized and at times de-energized depending on traffic conditions; and means including a check relay for checking the continuity of said coil upon each passage of a train; said means upon breakage of the continuity of said coil preventing said signal from again assuming the clear indicating condition after it has once assumed an adverse traffic indicating condition, in spite of the existence of more favorable traffic conditions ahead and so long as the continuity of said coil is broken. 70
27. In combination, a section of railway track, a trackway train controlling device comprising a winding, a first circuit controlled by traffic conditions in advance of said section for at times close circuiting said winding, a second circuit including said winding, and trackway governing means controlled by said second circuit. 80
28. In combination, a section of railway track, a trackway train controlling device including a winding, a first circuit for said winding controlled by traffic conditions and effective when closed to close circuit the winding, a second circuit including said winding and controlled by traffic conditions in advance, and trackway signaling means controlled by said second circuit. 85
29. In combination, a section of railway track, a trackway device for said section comprising a winding, a first circuit including said winding, a second circuit for at times close circuiting said winding, traffic governing means located in the trackway and controlled by said first circuit, and train carried governing apparatus controlled by said device according as said winding is on closed circuit or not. 90
30. In a train control system for railroads having tracks divided into blocks each provided with a normally closed track circuit, a roadside mechanism for each block comprising an energy transmitting device, a main circuit for governing the controlling condition of said device, an auxiliary circuit including part of said main circuit for indicating defective behavior of said device, relay means in said auxiliary circuit energized only if said circuit is intact, a three-position wayside semaphore signal for each block, a circuit for operating a signal from its danger to its caution position closed only if the relay means of the device of the corresponding block is energized, and means for effecting operation of said signal from the caution to the clear position independently of said relay means and auxiliary circuit. 100
